UNITED STATES PATENT OFFICE

ROBERT BERGER, OF PATERSON, NEW JERSEY

CIGARETTE CASE

Application filed June 16, 1928. Serial No. 285,904.

This invention relates to cases for holding cigarettes and similar elongated articles and delivering them one by one endwise through a single opening in the case, for which purpose the articles are usually held by a strap or equivalent means in a flat row against one broad wall, as the bottom of the case, and as each article is withdrawn through the opening a spring follower acting on the row of articles advances it so that another article takes the position of the one withdrawn. The invention consists in a novel construction of a case of this character and particularly in the means for ejecting the articles at said opening, the means for advancing the row of articles as each is withdrawn, and the means for controlling the advancing means at the time when the case is being loaded.

In the drawing,

- 20 Fig. 1 is a plan, partly in section, of the improved case, with the cover in open position; Fig. 2 is an end elevation of the case; Fig. 3 is a view in front elevation, partly in section on line 3—3, Fig. 1; 25 Fig. 4 is a fragmentary section on line 4—4, Fig. 1 (looking in the direction of the arrow); and Fig. 5 is a section on line 3—3, Fig. 1.

The body 1 of the case is a shallow rectangular box open at the top; its cover 2 is preferably also box-like in form, open at the bottom. The cover and case are hinged together at one long side of each, as at 3. The cover is designed to hold a reserve supply of cigarettes of about the same number as the body will hold when constructed as hereinafter set forth, wherefore the cover may have a material marginal filling or lining 2^a of any construction. When the cover is closed a spring 30 latch 4 on the front wall 1^a of the case engages the corresponding wall of the cover in a well-known manner and holds the cover closed, 5 being a button for repressing the latch to release the cover.

45 Lining the case at all sides and suitably secured therein are elongated tubular housings 6, 7 and 8. The housing 6 extends along the rear wall of the case from a point near the right-hand wall and then, being bent in a 50 curve, it extends along the left-hand side wall

to the front wall 1^a of the case; the housing 7 extends along the front wall from the front end of the housing 6 to near the housing 8; and the housing 8 extends along the right-hand end wall from the front wall to the 55 rear wall.

In the front wall near the right-hand end is the opening 9 through which the cigarettes are ejected. Preferably this opening is normally closed by a gate 10 having a thumb piece 10^a projecting through a horizontal slot 9^a in the front wall 1^a of the case and also having a stem 10^b (Figs. 1 and 4) projecting to the left into the housing 7, where it abuts a spiral spring 11 in said housing itself abutting the forward end of the housing 6. The gate may be guided (retained in a vertical plane) by a fork-shaped piece 13 which is secured as by screws 14 to the inside of front wall 1^a.

The cigarettes are ejected from opening 9 by an ejector 15 consisting of a block which normally stands between the right-hand end of housing 6 and the rear end of housing 8 and has a shank projecting horizontally through the housing 8 and a slot 16 (Fig. 2) in the right-hand end wall of the case, having a button 15^a exterior of the case.

When a cigarette is to be ejected the operator represses the gate 10 with the thumb of his right hand upon the thumb piece 10^a, so as to clear the opening 9, and then with his forefinger engaged with the button 15^a advances the ejector 15, so that a cigarette then opposed to the ejector 15 will be ejected. Ejector 15 is normally repressed by a spiral spring 17 (Figs. 1 and 2) interposed between it and the front end of the housing 8 and enclosed in the latter.

The cigarettes are placed in a flat row in a cavity formed by the bottom of the case and the housings 6, 7 and 8 so that each extends from front to rear of the case. The row is kept flat by a stiff but flexible strap 18 whose ends are removably held under clips 19. The row is normally pressed to the right, so that as each cigarette is removed through the opening 10 another will take its place, by a follower 20 which consists of a blade having a portion 21 which slides in housing

6 and protrudes through a horizontal slot 6^a in the front wall of the same. Portion 21 is subject to the pressure of a spiral spring 22 which is interposed between the same and 5 the front wall of the case, being contained in the housing 6 and therefore conforming to its bend. By extending the housing 6, with a bend, so that it reaches along the left-hand wall of the case as well as the rear wall the 10 spring may be of such length as not to have excessive power when the case is fully charged with cigarettes.

When the case is charged with cigarettes the follower 20 should be held retracted and, 15 in accordance with the invention, when the cover is then closed and secured by the latch 4 the follower should be released automatically. For this purpose a latch 23 is formed by forming a piece of flat metal with an enlargement 23^a engaged under the lip of a block 24 (Fig. 5) thus pivoting the latch, said piece being bent to form an upwardly bent hook 23^b. When the follower is repressed and is to be locked back the latch 25 23 is depressed until the follower may be caught by its hook 23^b, and upon release of the follower it rises under the pressure of a spring 25 and so holds the follower against the pressure of spring 22. When the cigarettes 30 have been placed in the case and the strap engaged with the clips 19 so as to hold the cigarettes down, on closing the cover 2 a lug 26 thereon encounters the latch 21 and, depressing it, releases the follower.

35 27 is a stiff but flexible strip like the strip 18 and removably held in place by clips 28 on the cover and serving to retain in the cavity of the cover the reserve charge of cigarettes.

40 Having thus fully described my invention, what I claim is:

1. In combination, a case body having a bottom and an upright surrounding marginal structure thereon formed with a straight 45 portion, a follower extending from said straight portion toward the opposite part of the marginal structure and movable along said straight portion substantially parallel with the bottom and held in such movement 50 by said portion in constant angular relation thereto, said structure having at the end of the case toward which the follower is thus movable an ejection opening arranged to permit one-by-one discharge of the articles 55 lengthwise of the follower, and means to eject each article when it registers with said opening.

2. In combination, a case body having a 60 polygonal bottom and an upright surrounding marginal structure thereon, a part of said structure being an elongated continuous housing extending along two adjoining sides of the bottom, a follower movable lengthwise of and guided by the portion of said housing 65 which adjoins one of said sides and project-

ing toward the opposite part of the marginal structure, a spiral spring in the housing having one end abutting the follower and normally urging the same toward the end of the case opposite the other of said sides and having its other end extending into the part of the housing adjoining said other side and opposed by a part of said body, said structure having at the end of the case toward which the follower is thus movable an ejection opening arranged to permit one-by-one discharge of the articles lengthwise of the follower, and means to eject each article when it registers with said opening.

3. In combination, a case body having a 80 rectangular bottom and an upright surrounding marginal structure thereon, said structure forming an elongated housing at each of three adjoining sides of the bottom, a follower movable lengthwise of and guided by one of the two housings which are opposed to each other and spring-pressed toward the third housing, said body having an ejection opening in the part of said structure having the other of said two housings and near the third housing, a spring-pressed gate guided by the other of said two housings and normally closing said opening, and a spring-retracted ejector arranged opposite said opening and guided by the third housing.

In testimony whereof I affix my signature.

ROBERT BERGER.
